[57] **CLAIM**

The ornamental design for the fan-foldable educational book for storing colors, as shown and described.

DESCRIPTION

FIG. 1 is a front elevational of the fan-foldable educational book for storing colors showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front elevational view thereof showing my design in the unfolded position;
FIG. 8 is a rear elevational view thereof showing my design in the unfolded position; and,
FIG. 9 is an enlarged view of a portion thereof with a crayon being shown inserted in its corresponding pocket thereof in broken lines merely to illustrate the use of the invention, with the crayon forming no part of the present invention. The indicia depicted by means of broken lines in FIGS. 1, 7, 8, and 9 has been illustrative purposes only and forms no part of the claimed design.
